UNITED STATES PATENT OFFICE.

ALLEN C. BRANTINGHAM, OF TOLEDO, OHIO.

ELEVATOR.

1,054,273.

Specification of Letters Patent. Patented Feb. 25, 1918.

Application filed March 7, 1910. Serial No. 547,748.

To all whom it may concern:

Be it known that I, ALLEN C. BRANTINGHAM, a citizen of the United States, residing at Toledo, Lucas county, Ohio, have invented a new and useful Elevator, of which the following is a specification.

This invention relates to disconnecting and stopping devices.

This invention has utility when embodied 10 in elevators, especially of the endless type.

Referring to the drawings: Figure 1 is a side elevation with parts broken away of an embodiment of the invention adapted to a passenger belt elevator, showing position 15 or the flight in normal travel; Fig. 2 is a view looking from the left toward the showing in Fig. 1; Fig. 3 is a fragmentary detail of some of the elements forming the brake actuating connections looking from the left 20 toward Fig. 2; and Fig. 4 is a side view of the invention similar to Fig. 1 with the frame structure eliminated, showing the abnormal or stop actuated position thereof.

The driver or belt 1 normally passes over 25 the pulley 2 fast to the shaft 3, which shaft 3 has fixed thereon the worm 4 in engagement with the worm wheel 5 mounted in the casing 6. The worm wheel 5 is fixed to shaft 7 to which shaft is also fixed the pulley 8 over which passes the elevator belt 9. This elevator belt 9 has hinged thereon passenger carrying flights 10 of right angle form which swing against the vertical reaches of the belt to provide platforms 30 upon which passengers may stand. Handholds 11 are provided on the belt 9 in convenient position for passengers riding up or down on the shelves or flights 10. Near the outer ends of each of the portions of the 35 flights 10 are extensions 12 coacting with the guides 13 on each side of the belt 9 which prevent the shelf portion of the flights 10 from inclining downward from the hinge should the belt 9 become a little slack.

A passenger aboard the flight 10 to the right of Fig. 1, should step off on the top floor 14, thus removing the load from the flight 10. As the continuously traveling belt causes the flight to move upward, the 45 angle lever 15 normally actuated by the spring 16 is a yieldable guide device of sufficient power to contact the flight extension 12 and guide it upward over the trigger element 17 to permit of the regular belt 50 running. This trigger 17 has a pin 18. The trigger 17 is pivotally mounted and

movable under the guide 19, which guide 19 has a slot 20 in which the pin 18 is movable. This slot 20, at its upper end, terminates in an angular portion deflected away from the belt 9 so that at this portion the pin 18 will cause the trigger 17 to be retracted out of the line of travel of the extension 12.

The trigger element 17 is pivoted at its lower portion upon rack carrying frame 22. 65 This frame 22 is in mesh with pinion 23 upon shaft 24. This shaft 24 carries a second pinion 25 in mesh with the gear segment 26 mounted upon shaft 27 parallel to the shaft 24. These shafts 24 and 27 are mounted in the framework between the guides 13. The segment 26 has a weight carrying arm 28. Mounted on the shaft 27 outside the guides 13 is an arm 29 to which may be adjustably connected the link 30 extending 70 to arm 31 forming with medial portion 32 and the second arm 33 a bell crank lever. Connected to the arm 33 of the bell crank lever is link 34 extending to the lever 35 pivotally carried by framework 36. This 75 framework 36 together with the elevator framework proper provides mounting for the shaft 3, while the shaft 7 is mounted directly in the elevator frame structure. This lever 35 is connected to the longitudinally 80 slidable bar 37 on the belt shifter which has the belt engaging fingers 38 to move the belt 1 from the fast pulley 2 on to the loose pulley 39, which loose pulley is carried by the shaft 3.

Fast to the shaft 24 outside the guides 13 is the arm 40 having the cross extension 41. Astride this element 40 and loosely mounted on the shaft 24 is the weighted element 42 having connected thereto the link 43 extending to the set screw held sleeve 44 on the longitudinally reciprocable rod 45. This rod 45 is mounted in the guides 46, 47. Adjustably connected to the rod 45 is the sleeve 48 to which is attached link 49 extending to 95 the angle lever 50. The angle lever 50 is connected to the friction brake strap 51 which has its opposite end firmly held by the bracket 52. The rack frame 22 is slidably mounted in the elevator structure and 100 has the upward extension 53 to which is connected the manually actuatable stop line 54 passing over the guide wheel 55. The line extends down beside the elevator belt 9 so that by pulling the line or cord 54 the 105 stop device may be actuated from any floor of the building. The weight 28 normally

holds the mechanism in shifted position of driving or not driving. To reset the stop device the line 56 may be manually actuated, which line 56 is connected to the extension 5 53 and extends down alongside the line 54. The brake 51 when set, is pulled by the angle lever 50 in the direction of travel of the brake wheel 57, with which the brake 51 coacts to stop the shaft 3 after the belt 1 10 is thrown on to the loose pulley 39. This sequence of operation is preserved owing to the fact that the brake connections are actuated through the weight 42 which is not thrown until the shaft 24 has made a rotation to cause the cross portion 41 to swing around the shaft and knock the weight away from the rest 58.

Operation: In the normal running of the elevator, passengers riding up will dismount 20 on the top floor 14 thus leaving the flight 10 unloaded so that spring 16 is strong enough to force angle lever 15 outward to guide the extension 12 laterally of the line of travel of the flight so that it passes over 25 the trigger element 17. Should the passenger thoughtlessly not dismount at floor 14, were no stop device provided such passenger would be flung over the top of the pulley 8, a mishap which has frequently occurred 30 with serious results. With the stop adjustment herein disclosed, should the passenger not dismount from the fastly moving elevator at top floor 14, the weight of such passenger will cause the extension 12 to bear so 35 firmly against the angle lever 15 as to overcome the resistance of spring 16 thus allowing the extension 12 to engage element 17 and haul it upward with the belt travel to 40 position as shown in Fig. 4. This actuation of the element 17 lifts the rack 22, actuating the driving pinion 23, shaft 24, segment 26, shaft 27, arm 29, link 30, to rock bell crank lever 31, 32, 33 to move link 34, thus 45 oscillating lever 35 to shift the bar 37 having the belt engaging fingers 38, and thereby move the driver or belt 1 from the fast pulley 2 on to the loose pulley 39. This means a most rapid and effective disconnecting of the driving power. Notwithstanding 50 the great resistance interposed by the worm gear speed reduction, the disconnection of the driving power may not insure stopping of the belt in time to avoid accident. This condition is especially liable to arise when 55 the momentum of the moving parts is increased by some of the downwardly traveling flights carrying passengers. To fulfill this requirement, there is incorporated in the stop device of this disclosure a locking means 60 to hold the elevator belt 1 from travel after the driving belt 1 is shifted to the loose pulley. This locking means is actuated from the shaft 24 by the arm 40. When the rack 22 has moved a sufficient distance to cause 65 the throw of the belt 1 off the fast pulley

2, shaft 24 has been rotated sufficiently to cause the cross portion 41 of the arm 40 to knock the weight 42 away from its upper position against the rest 58. As the weight 42 passes over the shaft 24, it is unbalanced 70 and free to fall or swing into downward position. This swing pulls the link 43 and through sleeve 44, rod 45, sleeve 48, link 49 and oscillating angle lever 50, draws the friction brake strap 51 against the brake wheel 57. This drawing is in the direction of travel of the brake wheel 57 and results in the quick stopping of the worm shaft 3. As weight 42 is tripped or actuated past its dead point to come into operation with a positive downward pull in insuring setting of the brake by full stroke action of the device, similarly the weight 28 serves to bring about a full and positive shifting of the belt off the fast or driving pulley. With the 80 elevator so stopped, the stop device actuating mechanism may be reset to permit normal travel by merely pulling the line 56. This will cause the rack 22 to move downward and through pinion 23 rotate shaft 24 to cause the cross portion 41 to pick up the weight 42 and swing it into upper position against its rest 58. This will release the friction wheel 57. During this operation, the pinion 23 through its connection with 85 the segment 26 has been effective to urge the driving belt 1 from the loose pulley 39 on to the fast pulley 2 to cause the elevator belt 9 to assume its normal running condition.

What is claimed and it is desired to secure 100 by Letters Patent is:

1. The combination with a flight, driving means including a flexible mounting for the flight, and a driver for the means, of a stop device therefor including mechanism disposed to be engaged and actuated by the flight to disconnect the driver from the means, and a guide device normally shunting the flight to avoid the stop device.

2. The combination with a normally continuously traveling belt elevator having flights pivoted thereto, driving means for the elevator, and a driver for the means, of a flight actuated stop device including mechanism actuated by a flight to disconnect the driver from the means and lock the means, and a guide device normally shunting the flight to avoid the stop device.

3. The combination with a normally continuously traveling belt elevator having flights pivoted thereto, driving means for the elevator, and a driver for the means, of a stop device including mechanism actuated by a flight to disconnect the driver from the means and then lock the means, and a guide device normally shunting the flight to avoid the stop device.

4. A belt elevator comprising a flight, a stop device for the elevator including mechanism disposed to be engaged and actuated 130

by the flight, and a guide device normally shunting the flight to avoid the stop device.

5. A belt elevator comprising a flight normally laterally movable as to its line of travel, and a stop device for the elevator including mechanism abnormally actuated by the flight.

10. A belt elevator comprising a flight, an automatic stop device for the elevator, and a second device as to which the flight may travel past said second device, including an element normally rendering the stop device inoperative.

15. A belt elevator comprising a flight, an automatic stop device for the elevator, and a yieldable device as to which the flight may travel past said yieldable device, including an element normally rendering the stop device inoperative.

20. A belt elevator comprising a flight laterally movable as to its line of travel, a stop device for the elevator and a device normally laterally moving the flight to cause it to pass the stop device.

25. A belt elevator comprising a flight, a stop device for the elevator including an element to engage the flight, and a guide device normally shunting the flight past the element.

30. 10. A belt elevator comprising a flight, a driver for the elevator, a stop device for the elevator including mechanism to disconnect the driver from the elevator, a device actuatable by the loaded flight to permit the flight 35 to operate the stop device, and a flight guide device operable to actuate the unloaded flight to avoid the stop device.

40. A normally continuously traveling endless belt elevator comprising a flight, a driver for the elevator, a flight actuated stop device for the elevator including mechanism to disconnect the driver from the elevator and lock the elevator against travel, and a flight guide device operable to actuate the unloaded flight to avoid the stop device.

45. 12. A belt elevator comprising a flight, a driver for the elevator, a flight actuated stop device for the elevator including mechanism acting in sequence to disconnect the driver from the elevator and then lock the elevator against travel, and a flight guide device operable to actuate the unloaded flight to avoid the stop device.

50. 13. The combination of a flight, driving means for the flight, a driver for the means, a stop device therefor including mechanism actuated by the flight to disconnect the driver from the means, loaded-flight actuated means normally rendering the stop device inoperative, and a rest device for the mechanism to effect connection of the driver to the driving means.

55. 14. A belt elevator comprising a flight, a stop device for the elevator including mechanism actuated by the flight, loaded-flight

actuated means normally rendering the stop device inoperative, and a reset device connected to the mechanism.

15. A belt elevator comprising a flight, a stop device for the flight including mechanism actuated by the flight and a device manually actuatable, which mechanism and manually actuatable device are connected to operate the stop device, and a guide device normally shunting the flight to avoid the stop device.

70. 16. A belt elevator comprising a flight, a stop device for the elevator including trip brake mechanism disposed to be tripped by the flight, and a guide device normally shunting the flight to avoid the stop device.

75. 17. A belt elevator comprising a flight, a driver for the elevator, a flight actuated stop device for the elevator including a trip mechanism for disconnecting the driver 80 from driving the elevator, and a guide device normally shunting the flight to avoid the stop device.

85. 18. A belt elevator comprising a flight, a flight actuated tripable stop device for the elevator, and a guide device normally shunting the flight to avoid the stop device.

90. 19. A belt elevator comprising a flight, a flight actuated stop device for the elevator, a guide for the stop device, and a guide device normally shunting the flight to avoid actuating the stop device along its guide, said stop device including a weight normally seating near its dead center position and in its tripping therefrom by actuation of the 100 stop device effective to supplement the travel of the stop device.

95. 20. A belt elevator comprising a flight, a flight actuated stop device for the elevator, and a guide device normally shunting the 105 flight to avoid actuation of the stop device, said stop device embodying drive disconnecting mechanism operating under a source of power of its own, brake mechanism operating under a source of power of its own, and 110 a member operable to actuate said mechanisms.

115. 21. In combination, a carrier the load on which is adapted to produce a lateral pressure and retarding means operating under a source of power of its own and adapted to be tripped by the movement of the carrier past a given point with a given pressure.

120. 22. In combination, a carrier including a laterally yieldable carrying member, the load on which is adapted to retain it in normal position, and retarding means operating under a source of power of its own and adapted to be tripped including a yieldable member adapted to engage the carrying member and only to permit actuation of the retarding mechanism when the carrying member is non-yielding with respect thereto.

125. 23. In combination, a carrier including a laterally yieldable carrying member, the 130

- lead on which is adapted to retain it in normal position, and regarding means operating under a source of power of its own and adapted to be tripped including a pivoted 5 guard, a yieldable member adapted to engage the guard and only permit actuation of the retarding mechanism when the carrying member is non-yielding with respect thereto.
- 10 24. In combination, a carrying belt, a carrying member pivoted thereto, a trip adapted to be engaged by the member, a yieldable guard member adapted to swing an unloaded member away from the trip, 15 and retarding means connected to the trip and operating under a source of power of its own and adapted to be tripped.
25. In combination, an endless belt, a carrying member pivoted thereto, having 20 two reversible platforms one being adapted to abut the belt, while the other projects outwardly therefrom, and retarding means operating under a source of power of its own and adapted to be tripped by lateral 25 pressure of the platform against the belt when the opposite platform is loaded.
26. In combination, an endless belt, a carrying member pivoted thereto, having two reversible platforms, one being adapted 30 to abut the belt while the other projects outwardly therefrom and retarding means operating under a source of power of its own and adapted to be tripped by lateral pressure of the platform against the belt when the 35 opposite platform is loaded, said retarding means including a trip and a yieldable guard member normally tending to force the platform away from the trip.
27. In combination, an endless belt, a carrying member pivoted thereto, having 40 two reversible platforms, one being adapted to abut the belt while the other projects outwardly therefrom and retarding means operated by lateral pressure of the platform 45 against the belt when the opposite platform is loaded, said retarding means operating under a source of power of its own and including a trip and a yieldable guard member tending to force the platform away from 50 the trip, said guard member having an inclined portion lying in the path of the carrying member.
28. In combination, a carrying belt, a carrying member pivoted thereto, a trip 55 adapted to be engaged by the member, a yieldable guard member adapted to swing an unloaded member away from the trip, and belt retarding means connected to the trip said means operating under a source of 60 power of its own.
29. In combination a continuous belt carrier, a trip adapted to be actuated thereby only when the carrier is loaded, a weighted member adapted to be disengaged by the trip, and a belt shifter actuated by the drop 65 of the member.
30. In combination, a continuous belt carrier, a trip adapted to be actuated thereby only when the carrier is loaded, a weighted member supported in raised position and 70 adapted to be shifted by the trip, driving means, a brake for the carrier, and means operated by the shifting of the weighted member for disengaging the driving means and applying the brake. 75
31. In combination, a continuous belt carrier, a trip adapted to be actuated thereby only when the carrier is loaded, a weighted member, means for supporting same in raised position adapted to be disengaged by 80 the trip, driving means including a belt, a belt shifter for said driving belt, a brake for the carrier, and connecting means operated by the drop of the weighted member for disengaging the driving means and applying the brake, said connecting means including a shaft and levers on the shaft connected to the brake and belt shifter. 85
32. In combination a continuous belt carrier, a trip adapted to be actuated thereby 90 only when the carrier is loaded, a weighted member adapted to be disengaged by the trip, a drive disconnecting means actuated by the drop of the member, and manually operable means for restoring the weighted 95 member to normal position.
33. In combination, a continuous belt carrier, a trip adapted to be swung thereby only when the carrier is loaded, a weighted member adapted to fall when the trip is actuated, 100 and a drive disconnecting means actuated by the weighted member in falling.
34. In combination, a continuous belt carrier, a trip adapted to be actuated thereby only when the carrier is loaded, a weighted 105 member adapted to be disengaged by the trip, a drive disconnecting means, and a brake actuated by the drop of the member.
35. A carrier, a flight connected to the carrier, a stop device for the carrier, and a 110 guide for the flight in its travel with the carrier, said guide including a section yieldable to loaded flight action thereby to permit the flight to actuate the stop device.
- In witness whereof I affix my signature 115 in the presence of two witnesses.

Correction in Letters Patent No. 1,054,273.

It is hereby certified that in Letters Patent No. 1,054,273, granted February 25, 1913, upon the application of Allen C. Brantingham, of Toledo, Ohio, for an improvement in "Elevators," an error appears in the printed specification requiring correction as follows: Page 3, line 60, for the word "rest" read *reset*; and that the said Letters Patent should be read with this correction therein that the same may conform to the record of the case in the Patent Office.

Signed and sealed this 1st day of April, A. D., 1913.

[SEAL.]

C. C. BILLINGS,
Acting Commissioner of Patents.
